UNITED STATES PATENT OFFICE.

PAUL JACQUES MATHURIN GIRAULT, OF PARIS, FRANCE.

METHOD OF STARTING AND REGULATING THE SPEED OF INDUCTION-MOTORS.

SPECIFICATION forming part of Letters Patent No. 730,108, dated June 2, 1903.

Application filed October 3, 1901. Serial No. 77,423. (No model.)

To all whom it may concern:

Be it known that I, PAUL JACQUES MATHURIN GIRAULT, engineer, a citizen of the French Republic, residing at Paris, France, (post-office address 71 Rue Damremont, Paris, XVIIIe), have invented certain new and useful Improvements in Methods of Starting and Regulating the Speed of Induction-Motors, of which the following is a specification.

10 This invention has for its object to provide an improved method for starting and regulating the speed of induction-motors with revolving inducing-fields which are fed by simple or polyphase alternating currents. These 15 motors have a sufficiently high starting torque without any undue consumption of current and at the same time have the coils of their inducing-fields closed on themselves and of resistance as small as may be desired. In the 20 application of these arrangements the motor must consist, essentially, of two motors, (hereinafter called the "component" motors,) the corresponding polyphase induced-field windings of which are connected in series, while the 25 inducing-windings are so arranged as to exercise on the common induced circuits a concordant action when the motor is working at its normal speed. The revolving parts or rotors of the component motors are connected 30 mechanically, so as to insure the same slip relatively to the stationary parts or stators. When the motor is being started, only the 35 circuits of the inducing-field of the first motor (hereinafter called "principal" motor) are fed directly, while the inducing-circuits of the other motor (hereinafter called the "auxiliary" component motor) are open. Under these circumstances very high electromotive forces are induced in the induced circuit of 40 the principal motor. These electromotive forces act on the induced circuits of the auxiliary motor, and said induced circuits act at this time as a strong self-induction coil, for the reason that the inducing-circuits of the 45 auxiliary motor are open. The strength of the current corresponding to the electromotive forces in the induced circuits of the principal motor is consequently weak. The couple of the whole apparatus is thereupon increased (or the angular velocity for a given 50 resisting-couple is then increased gradually) by increasing little by little the excitation of

the inducing-fields of the auxiliary component motor until this said excitation reaches its normal value. I may obtain these results 55 by the methods hereinafter described.

First. In each of the circuits of the inducing-field of the auxiliary motor I introduce a rheostat or a reactance-coil and the resistance or the inductance will be gradually decreased. To simplify matters, the rheostats or the coils of the various circuits may be combined. For instance, in the case of an N-phase motor it will be possible if rheostats be used to group these rheostats in one single apparatus and operate simultaneously and in the same way each one of the N-phase circuits or operate alternately each one of them, so as to obtain a greater number of distinct positions for the same number of contacts of the rheostat. If reactance-coils be used, (the case of an N-phase polyphase motor being still presumed,) it is possible to operate first the rheostats in the manner already explained and to replace in the well-known 75 manner the N single-phase alternate-current coils by a single N-phase coil.

Second. Each of the circuits of the inducing-field of the auxiliary motor may be fed by a transformer of any kind having a variable ratio of transformation, which transformer may be provided with one kind of winding or with both primary and secondary windings. It is also possible in the case of an N-phase motor to replace the N single alternating-current transformers by a single N-phase transformer. In this case care should be taken to switch in resistances or reactances, at least in the section or sections of the transformer or transformers which feed the inducing-fields under the smallest differences of potential; otherwise the risk would be run that the intensity absorbed by the principal motor would undergo too great a variation.

Third. Each of the inducing-circuits of the auxiliary motor may be connected in series with the corresponding inducing-circuit of the principal motor, and the number of coils of the auxiliary inducing-field may be caused to vary from zero at the time of starting to 100 the maximum number required when working under normal conditions. In this case the value of the revolving flux of the inducing-field of the principal motor is not con-

stant during the starting operations, as in the two previous cases. For instance, if the auxiliary motor is as regards construction identical with the principal motor the revolving flux of the principal motor will when the motor is started have a value which is practically double its normal value.

With regard to the three methods just described the following remark, which might have in some measure been anticipated from the foregoing, may be made. In the case of polyphase (N-phase) motors it is possible to effect simultaneously and in the same manner the operations already described on the N-phase inducing-circuits or, again, (in considering the whole of the said operations as effected by a series of successive jumps) operate during the interval of a jump alternately in each one of the inducing-circuits, so as to have a greater number of distinct positions for the same number of contacts. In the case of a single alternating-current motor it is likewise possible to effect the aforesaid operations simultaneously and in a like manner on the various inducing-circuits or alternately on each one of them in the interval of a jump.

In the description which follows and in which the accompanying drawings will be referred to various constructional forms of the motor will be given which are appropriate to the carrying out of the aforesaid three methods. The reasoning will apply in each case both to a single circuit of the inducing-fields and to the corresponding circuit of the other inducing-field, and I will presume that analogous operations are effected simultaneously or alternately, as already stated, in the interval of a jump on all the other corresponding inducing-circuits of the two component motors. The examples given will therefore obviously apply to all the types of single or polyphase alternate-current induction-motors with revolving circular or elliptical inducing-field. I need not dwell on the simplifications which may be easily made in the case of polyphase currents. To simplify matters, I will presume that in the following examples the two component motors are of identical construction, and I will presume that the two induced fields consist of one single squirrel-cage, which will constitute for the induced fields a special case of two squirrel-cage windings connected in series.

Figure 1 shows two component motors A_1 and A_2 , constructed in accordance with the foregoing description, A_1 being, for instance, the principal motor and A_2 the auxiliary motor. In this figure the inducing-fields a_1 and a_2 are stationary—i. e., they constitute the stators, while the induced fields b_1 and b_2 constitute the rotors. Let c_1 be one of the inducing-circuits of the principal motor A_1 and let c_2 be the corresponding inducing-circuit of the auxiliary motor A_2 . The various inducing-circuits of the two motors I shall call $c_1 c'_1 c''_1$ and $c_2 c'_2 c''_2$, &c., respectively.

In all the figures the arrows indicate the direction of the movements that have to be imparted to the corresponding handles in order to pass gradually from the switching-in circuit of the motor to the position corresponding to normal working.

Fig. 2 shows a diagram relating to my aforesaid first method. On starting the motor the whole of the resistance e is switched in or the circuit can even be entirely broken—that is to say, the resistance can be rendered infinitely great. The current is, for instance, switched on by closing switch g , and the resistance e is decreased gradually by moving the handle f until the motor starts. The angular velocity is caused to vary by a further movement of the handle f . Lastly the normal or maximum speed corresponding to a given torque is obtained when the handle f is at the end of its stroke on the side corresponding to the zero value of the resistance e .

Fig. 3 shows a diagram relating to my aforesaid second method. In this figure, c_1 and c_2 are the two corresponding inducing-circuits. c_1 is fed directly, while c_2 is fed by the transformer e under gradually-increasing differences of potential produced by operating the handle f . According to the arrangement shown in this figure the transformer is, more correctly speaking, an "autotransformer," for it has only a single winding. Of course the handle has to be provided with a cutting-off device similar to that used in connection with accumulator cell-cutting-off switches. Moreover, care is taken to feed the circuit c_2 through the transformer e only when the rheostat h , whose resistance is variable, is switched in circuit with c_2 . If this rheostat were suppressed when the first sections of the transformer e are switched in circuit with c_2 , the electromotive force due to e could be left out of consideration relatively to that due to the mutual induction of c_2 and of the inducing-field of the auxiliary motor A_2 , (for c_1 being switched in the circuit acts on both inducing-fields and the inducing-field of A_2 acts in its turn on c_2 .) As c_2 would then be closed on a very small resistance, heavy currents could be generated in c_2 , and consequently also in the inducing-fields and in c_1 , which would be contrary to the purpose in view. Care is therefore taken to switch in the whole of resistance h before switching in, and in order to effect the starting of the motor the handle f is operated in such a manner that it does not connect any section or even only the first section of the transformer e with c_2 . The switch g is then closed, and both the intensity of the current and the torque (or the speed for a given resisting couple) are gradually increased by increasing the number of active sections of the transformer e through the operation of the handle f and the simultaneous corresponding and gradual decrease of the resistance h , effected by moving the handle i . The normal or maximum speed which approximates synchronism

is attained when both handles *f* and *i* are at the end of their traverse, so that all the sections of *e* are active and the resistance of *h* is annulled. Of course the resistance *h* might be replaced by a variable reaction coil, the precautions mentioned in the foregoing being observed. Instead of operating simultaneously the handles *f* and *i* the handle *f* might be first operated alone and when it has reached the end of its traverse *i* might then be operated alone. It is also possible to act successively and at different times on *f* and *i*, the whole of these manipulations being carried out so as to obtain variations of the current and torque according to a predetermined law. Lastly it should be remarked that under certain circumstances the value of the resistance *h* might be very small, even zero, as would be the case if the dimensions of the auxiliary motor were very small when compared with those of the principal motor.

Fig. 4 is a diagram relating to my aforesaid third method. In this figure the inducing-circuit *c'* has a constant number of active coils, while the number of active coils of *c*² is gradually varied by the movement of the handle from a zero value at the time of starting the motor to the normal value. In order to avoid too large a number of handles and fixed contacts in the case of multipolar motors, each portion of the circuit *c*₂ corresponding to the various poles is divided into a certain number of sections, which number would for each pole be equal to the number of variations to be effected. According to cases the similarly-situated sections are connected in series, Fig. 5, or in parallel. In Fig. 5 the case is presumed of one of the three inducing-windings of a three-phase motor. The free wire ends *x y z u* at the top of the figure should be connected to the fixed contacts, over which the handle *f* of Fig. 4 is moved. The circular connections of Fig. 5 might be replaced by involute connections.

Each one of my three aforesaid methods might be carried into practice by means of suitably-arranged transformers for altering the voltage. With the reservations already made Figs. 6 to 9 show these modifications. Fig. 6 corresponds to Fig. 2, Figs. 7 and 8 to Fig. 3, and Fig. 9 to Fig. 4. The winding *c*₁ is fed through the medium of a transformer whose primary winding is designated by *p*₁ and the secondary winding by *q*₁. The winding *c*₂ is fed, respectively, in each case in accordance with my first and second methods, respectively, by means of a transformer whose primary and secondary are designated, respectively, by *p*₂ and *q*₂. In Fig. 7 the winding *q*₂ corresponds to the winding *e* of Fig. 3. It will be noted that if in the arrangement shown in Fig. 7 the handle *f* is moved the number of inactive coils of the secondary winding *q*₂ increases as the handle *f* is moved farther away from the position which corresponds to normal working. The arrangement shown in Fig. 8 permits of utilizing for the winding

*c*₁ the inactive coils which are opposite the winding *c*₂. The potential at which *c*₁ is fed becomes thus higher as that of *c*₂ becomes lower in the same manner as obtains in the case of my aforesaid third method, Fig. 4. In Fig. 9, which shows a modification of my third method, there are again two transformers the primary windings of which are *p*₁ and *p*₂, while the secondary windings *q*₁ and *q*₂ are series connected. The characteristic feature of the four modifications shown in Figs. 6 to 9 is the use for each pair of corresponding inducing-windings of two transformers whose primaries are fed in parallel.

The modifications shown in Figs. 10 to 13 correspond, respectively, to those shown by Figs. 6 to 9—namely, that shown in Fig. 10 corresponds to Fig. 6, that shown in Fig. 11 to Fig. 7, that shown in Fig. 12 to Fig. 8, and that shown in Fig. 13 to Fig. 9. The common difference between these two kinds of modifications lies in the fact that in the modifications shown in Figs. 10 to 13 the primary windings *p*₁ and *p*₂ are connected in series.

The modified forms shown in Figs. 14 to 17 correspond, respectively, to the former as follows: That shown in Fig. 14 corresponds to the arrangements shown in Figs. 6 and 10, that shown in Fig. 15 to those shown in Figs. 7 and 11, that shown in Fig. 16 corresponds to those of Figs. 8 and 12, and that shown in Fig. 17 corresponds to those shown in Figs. 9 and 13. The essential feature of the further modifications shown in Figs. 14 to 17 resides in the fact that the two transformers are reduced to a single one, the primaries *p*₁ and *p*₂ being combined into a single primary *p*.

For the modification shown in Figs. 6 and 7, 10 and 11, 14 and 15 the secondary windings *q*₁ and *q*₂ may be either independent, as shown in Figs. 6 and 7, or connected in series, as shown in Figs. 10 and 11, 14 and 15, and in this second case the corresponding windings *c*₁ and *c*₂ are also connected in series, and a conductor *r s* connects together the points *r* and *s*, which are respectively the points of connection of the windings *q*₁ and *q*₂ and *c*₁ and *c*₂.

All the modifications shown in Figs. 6 to 17 may be according to the case simplified by using single windings for the transformers in lieu of separate primary and secondary windings. Lastly only one of the windings *c*₁ or *c*₂ may be fed directly from the line, while the other is fed through the medium of a transformer.

The carrying into practice of my first and second methods may be modified by connecting the windings *c*₁ and *c*₂ in series after the starting operations are completed. Thus Figs. 18 and 19 correspond to Fig. 2 (first method) and Fig. 20 to Fig. 3, (second method.) Feeding may be effected for the whole installation directly from the line or through the secondary of a transformer. In Figs. 18 and 19 the current flows directly into the winding *c*₁ at the moment of starting, the winding *c*₂

being closed through a large resistance. As the starting operations are proceeded with the winding c_2 is getting gradually switched in the circuit in series with c_1 , this being effected by means of two handles in the arrangement shown in Fig. 18 and by means of a single handle in that shown in Fig. 19. In the latter arrangement once the handle has been operated the switch t can be opened.

10 In other words, the resistance of the part of the circuit running from the handle f to the end s of the winding c_2 is gradually increased and the resistance of the part of the circuit running from f through the resistance h and 15 the handle i to the other end of the winding c_2 .

In Fig. 20 the difference of potential at the terminals of the system consisting of the winding c_2 and of the resistance h increased 20 gradually, while at the same time the resistance h , switched in the circuit of this winding, is being decreased. It will be noted that in the case shown in this figure and in that shown in Figs. 10 and 11 the actions resulting 25 from these manipulations are of a complex nature, owing to the fact that a gradually-decreasing self-induction is being introduced in circuit c_1 .

All the cases I have considered necessitating 30 the use of transformers these may of course undergo the simplifications that are in general use in polyphase-current practice—such as, for instance, the substitution of an N -phase transformer for N single-phase transformers.

In all the cases that have been considered unequal component motors may be used. If the two component motors have a common shaft, they will necessarily have the same 40 number of poles; but the diameters to which the stationary parts are bored may be different and the width of the core-iron sheets may also be different. The component motors may then have different numbers of poles; 45 but it will then be necessary to connect them by mechanical means in such a manner that the ratio of their angular velocities be equal to the inverse ratio of the number of their poles. (This result may be obtained by 50 means of wheel-gearing.) This condition is sufficient; but it will be besides advisable to give to the two component motors, at least in the neighborhood of synchronism, curves of variations of power proportional, or nearly 55 proportional, to the slip, this being done for the purpose of insuring a better utilization of the materials. The rotor may in each of the component motors be either the inducing-field or the induced field. It is therefore 60 possible to realize all the combinations that are possible. The induced windings of the one or the other component motors may be of any kind allowing of the corresponding circuits of the induced field being connected 65 in series. For instance, squirrel-cage induced fields or rotors may be used, as shown in Fig. 1, or the coils may be closed on them-

selves and be of the ring-armature pattern, Fig. 21, or drum-windings may be used. Ring or drum polyphase windings or polyphase windings analogous to those of the armatures of direct-current dynamos may also be used.

To conclude the description of my invention I would remark that the same relates, essentially, to a motor (principal motor) whose induced circuits contain very high self-inductances, (constituted by the induced circuits of the auxiliary motor.)

To start this motor and increase the speed for a given torque, I decrease the influence of these self-inductances until it has entirely disappeared, this being obtained by gradually increasing the excitation of the auxiliary motor. By my process the parts which constitute and act as self-inductances when the motor is first started become, therefore, more and more active as the hereinbefore-described operations are being carried out. Of course as in all the methods invoking self-inductances switched in the circuits of the induced field I may shunt the induced circuits of my principal motor and through this shunt also the self-inductances (induced circuits of the auxiliary motor) by means of resistances of constant value and sufficiently large to produce an initial torque of sufficient magnitude to insure the starting of the motor. For example, when squirrel-cages are employed, as shown in Fig. 22 of the drawings, a ring d' of sufficiently great resistance may be used, or when polyphase induced windings are employed the induced circuits $d_1 d_1 d_1$ of the principal motor may be shunted by resistances $d' d' d'$, as shown in Fig. 23. In Figs. 22 and 23 $d^2 d^2$ indicate the induced windings of the auxiliary motor.

Having now particularly described and ascertained the nature of my said invention and in what manner the same is to be performed, I declare that what I claim is—

The method of starting and regulating the speed of induction-motors made up of a plurality of component motors having polyphase induced-field windings connected in series, which consists in supplying with current at the moment of starting, the inducing-field of only one of said component motors, the inducing-field of the other component motor being at such time in an open circuit, the inducing-fields being so arranged as to exercise on the common induced circuits a concordant action when the motor is working at its normal speed, and afterward, as the speed of the motor increases, increasing the excitation of the inducing-field of the second component motor from zero to its normal value.

In testimony whereof I have hereunto set my hand in presence of two subscribing witnesses.

PAUL JACQUES MATHURIN GIRAUT.
